UNITED STATES PATENT OFFICE.

CHARLES MEMMERT, OF WASHINGTON, DISTRICT OF COLUMBIA.

BEDROOM SANITARY CLOSET.

SPECIFICATION forming part of Letters Patent No. 364,430, dated June 7, 1887.

Application filed March 19, 1887. Serial No. 231,581. (No model.)

To all whom it may concern:

Be it known that I, CHARLES MEMMERT, a citizen of the United States, residing at the city of Washington, District of Columbia, have 5 invented certain new and useful Improvements in Bedroom Sanitary Closets, of which the following is a specification, reference being had to the accompanying drawings, in which—

Figure 1 is a perspective of a portion of an 10 apartment, showing the mantel piece, its fire-board, and my improved closet secured thereto. Fig. 2 is a sectional view showing my improved closet projecting into the chimney or flue through the brick-work near the floor-line. Fig. 3 is a perspective view of my improved closet detached.

The object of my invention is to provide sleeping-apartments with a closet set in the fire-board or wall and extending into and communicating with the chimney or flue, to form a receptacle for the chamber-pot, so that the same will be out of sight and all odors therefrom will pass up the chimney.

The invention will be first described, and 25 then specifically pointed out in the claims.

A represents my improved closet projecting into the flue or chimney 1, either through the brick-work 2, as shown in Fig. 2, or through the fire-board 3. (Shown in Fig. 1.) In either 30 case the closet is placed near the floor-line.

The closet is made of any suitable material, preferably sheet metal, and has an open front to the flange *a*, around the edge of which, at one side, is hinged the door *B*. The lower 35 part of the door is provided with small holes *b*.

The closet is provided in the upper part of its rear wall with an opening, *C*, so that a current of air will pass from the room through the holes *b* and opening *C* into the flue, and 40 thereby carry off all odors and gases from the chamber-pot, as shown in Fig. 2.

In order that the updraft in the flue may not prevent the gases from passing out through the opening *C* at any time, I provide a lip or flange, *D*, at the lower side of the opening, the lip projecting at right angles to the back of the closet.

In practice the closet will be nine inches deep, nine inches wide, and seven and one-half 45 inches high, so that when in place it will not project into the flue more than four inches, and the rear end of the closet is rounded,

so that it will not interfere with the draft in the slightest.

When in place, the flange *a* rests close against 55 the fire-board or plastering, as the case may be, so that the closet will not take up any space in the compartment.

The vessel referred to is ordinarily placed under the bed; but by my improvement it may 60 be placed entirely out of sight, and yet where it may be readily removed for use, after which it may be replaced in the closet, and the odors and gases pass up the flue.

It is especially useful in sick-rooms, where 65 it is impossible to instantly remove the vessel containing fecal deposits.

I am aware that a water-closet has been provided with a pipe leading into a flue, the pipe having an upwardly-extending deflector at its 70 lower side within the flue; also, that a chair has been provided with a privy-seat, a casing or receptacle below the same, an apertured door hinged to the front of the casing, and a pipe leading from the rear of the casing into 75 the flue; also, that a chimney or flue has been provided with a casing set into the brick-work, and having a door hinged at its open front and closed at every part within the flue, except at its bottom, which was open and provided with 80 a cage depending into the flue. Within the casing was placed a drawer-frame having a hinged privy-seat and a vessel constructed to dump its contents down into the cage in the flue when the drawer and privy-seat were 85 moved within the casing, and I do not claim any of said constructions as of my invention.

Having thus described my invention, what I claim as new, and desire to secure by Letters Patent, is—

1. The combination, with a chimney or flue having an opening communicating with the interior of a room, of the chamber-receiving closet set in the said opening flush with the inside of the room, projecting into the flue, and having an opening in its rear upper end, and a hinged apertured door at its open front end, the closet being otherwise closed, substantially as set forth.

2. A sanitary closet adapted to project into 100 a flue formed with an open front, a rounded rear end, an opening, *C*, in the upper part of said rear end, a flange, *D*, projecting outward from the lower edge of the opening, the flange

a around the open end of the closet, and the door *B*, hinged at one side thereof and provided with holes *b* near its lower edge, substantially as set forth.

5 3. The combination, with an apartment having an opening near the floor-line leading into the flue, of the open-front sanitary closet set into the said opening flush with the inside of

the room, to receive a separate and disconnected vessel of the character set forth, and to communicating with the room and flue, substantially as set forth.

CHARLES MEMMERT.
